CLAIM

The ornamental design for a positive airway pressure delivery console, as shown and described.

DESCRIPTION

FIG. 1 is a front perspective view of a positive airway pressure delivery console showing our new design in a first embodiment;

FIG. 2 is a front view thereof from the reverse perspective;

FIG. 3 is a rear perspective view thereof;

FIG. 4 is rear view thereof from the reverse perspective;

FIG. 5 is a top view thereof;

FIG. 6 is a bottom view thereof;

FIG. 7 is a front view thereof;

FIG. 8 is a rear view thereof;

FIG. 9 is a right side view thereof;

FIG. 10 is a left side view thereof;

FIG. 11 is a right side view from the right, front bottom perspective; and,

FIG. 12 is a another right side view from the right, rear bottom perspective.

The broken lines depict portions of the positive airway pressure console and do not form a portion of the claimed design.

1 Claim, 12 Drawing Sheets
